AUTOMATIC HUMIDIFIER

Herman W. Patterson, Cleveland Heights, Ohio

Application April 1, 1936, Serial No. 72,154

15 Claims. (Cl. 261—106)

This invention relates to humidifying apparatus and, more particularly, to an improved humidifying device which is automatic in operation.

An object of this invention is to provide an improved humidifying device having a foraminous absorbent screen through which air may be forced and which is movable to an operative position by the flow of air.

Another object of this invention is to provide improved humidifying apparatus having a foraminous absorbent screen which is movable to an operative position by the flow of air and which has a portion movable into cooperation with a liquid supply by such movement of the screen.

A further object of this invention is to provide improved humidifying apparatus, of the type referred to, wherein a chamber having float controlled valve means furnishes a substantially constant level liquid supply for the foraminous screen.

Still another object of this invention is to provide an improved humidifying device, of the type mentioned, wherein an electrically operated fan forces air against and through the foraminous screen and wherein a humidostat automatically causes starting and stopping of said fan.

It is also an object of this invention to provide an improved humidifying device having an air passage with liquid supply and collecting containers adjacent the top and bottom thereof and wherein a foraminous absorbent screen through which air is adapted to be forced is mounted to swing in the passage from one transverse position to another such that when in one of its transverse positions it receives liquid from one container and when in the other of its transverse positions it receives liquid from the other container.

Other objects and advantages of the invention will be apparent from the following description when taken in conjunction with the accompanying sheet of drawings, wherein

Fig. 1 is a front elevation of a humidifying device embodying my invention.

Fig. 2 is a vertical sectional view taken on line 2—2 of Fig. 1.

Fig. 3 is a partial vertical sectional view showing the screen hinge structure on a larger scale.

Fig. 4 is a similar partial vertical sectional view showing the float operated screen latch on a larger scale, and

Figs. 5 and 6 are side elevational views of my improved humidifying device showing air directing hoods mounted thereon.

In the accompanying drawing, to which more

detailed reference will presently be made, I have shown what I now regard to be a preferred form of my improved automatic humidifying apparatus. However, before proceeding with such more detailed description it should be understood that the invention is not to be regarded as limited to the particular apparatus herein disclosed but may be embodied in various other devices and apparatus.

As shown in Figs. 1 and 2 of the drawing, my improved humidifying apparatus includes a casing or housing 10 of sheet metal or other suitable construction and having an air passage 11 therein. Portions of the casing may be arranged to form vertical and inclined walls 12 and 13 adjacent one end of the passage 11. These walls have discharge openings 14 and 15 therethrough and are spaced apart to provide therebetween a chamber 16 with which these discharge openings communicate. The opposite end of the passage 11 may be left open to provide an air intake.

Air may be caused to flow into the passage 11 and through the openings 14 and 15 by any suitable forcing means, but I find that an electric fan 18 is satisfactory for this purpose and may be conveniently mounted directly in the passage 11 of the casing 10. The electric fan 18 may be mounted in the passage 11 by means of suitable brackets 19 connected with the vertical wall 12 so as to locate the impeller of the fan adjacent the opening 14.

The casing 10 may be constructed to provide a liquid containing chamber or tank 20 immediately above the passage 11 and to also provide a liquid collecting container or pan 21 immediately below the passage 11. The tank 20 is preferably constructed with an opening 22 through the front wall 23 thereof. The collecting container 21 may be constructed to extend laterally beneath the bottom wall 24 of the passage 11 and across the bottom of the chamber 16. The casing 10 may also be provided with a liquid supply reservoir 26 at an elevation above the tank 20. This reservoir may be formed in the upper part of the casing itself and may be provided with a discharge pipe 27 so that liquid may be supplied by gravity from the reservoir to the tank 20. The level of liquid in the tank 20 may be controlled and automatically maintained at a substantially constant level. Any suitable means may be employed for this purpose, such as a valve 28 which is operated by movement of a float 29.

For supplying the liquid to the air delivered by the electric fan 18, I provide an absorbent foraminous wick or screen 30 which, in accordance

with my invention, is arranged to have air forced therethrough by the operation of the electric fan. This screen is mounted for swinging movement and extends downwardly into the chamber 16 in transverse relation to the discharge openings 14 and 15. The screen may be of any suitable form of construction and may, for example, comprise a suitable marginal frame 31 upon which a foraminous absorbent web 32 is stretched or otherwise mounted. The frame may be of wire bent to the desired shape or outline, or may be of any other suitable construction. The web 32 may be a woven fabric or any other suitable material of sheet or web form which will serve as a wick for conducting liquid by capillary action.

The screen 30 may be mounted for the desired swinging movement by providing the same with a transversely extending hook-like member 34 which engages the upper edge of the front wall 20 of the supply tank 20. The transverse member 34 may be connected with the marginal frame of the screen and, in addition to its function as a hinge member, may serve to reinforce and strengthen the screen. This hinge member may be provided at its ends with forwardly extending handles 35 which may be conveniently grasped for the purpose of lifting the screen when it is to be moved into or out of its suspended position on the front wall of the supply tank 20, such as might be done when one screen is to be replaced by a clean screen or one of different absorptive characteristics.

As an important feature of my invention I construct the screen 30 with an angularly or rearwardly extending portion 36 which extends into or overhangs the tank 20 when the screen is hingedly supported on the front wall thereof, as shown in Fig. 2. This angularly extending portion 36 is adapted to dip into the supply of liquid in the tank 20 so that the liquid will be picked up by the screen and supplied to the air which is forced through the screen by the electric fan. The handles 35 may be weighted or may be constructed to contain a sufficient body of metal to counterbalance the angularly extending screen portion 36. This causes the downwardly hanging part of the screen to assume a rest position close to the vertical wall 12.

In the operation of my improved humidifying apparatus the starting of the electric fan 18 causes air to be delivered against the screen 30 which, in its rest position, hangs down immediately in front of the discharge opening 14 as shown in full lines in Fig. 2. The force of the air against the screen causes the same to swing to its dotted line position across the opening 15 of the inclined wall 13. The air delivered by the fan is forced into the chamber 16 and then out through the openings of the foraminous screen. Movement of the screen to its dotted line position across the opening 15 causes the angularly extending portion 36 to dip into the liquid of the tank 20. As long as the electric fan 18 continues in operation the screen will be held in its position across the opening 15, with the portion 36 extending into the liquid of the tank 20. While the screen remains in this position liquid will be picked up from the tank 20 and will travel downwardly through the screen to be transferred to the air being forced therethrough by the fan. When the fan 18 is stopped the screen 30 swings back to its rest position, thereby lifting the portion 36 out of the liquid of the tank 20 and discontinuing the supply of liquid to the screen.

Starting and stopping of the electric fan 18

may be brought about by manual manipulation of a control switch 38 but I prefer to provide means for causing automatic starting and stopping. This means may include a humidostat 39 which is located at a desired point and which is electrically connected with the fan 18 by the conductor cable 40. When the air of the room in which the apparatus is located, becomes too dry, the humidostat 39 acts to automatically start the fan 18. If the air of the room becomes too moist the humidostat again acts to automatically stop the electric fan.

In the use of my improved humidifying apparatus it may be found that liquid travels down the screen 30 from the tank 20 at a rate faster than 15 it is picked up by the air being forced through the screen. The excess liquid flows or drips from the screen and collects in the container 21. The collected liquid may be drained or otherwise removed from the container 21, but I prefer to provide means whereby the supply of liquid to the screen from the tank 20 may be interrupted for a period of time while liquid is supplied to the screen from the collecting tank. For this purpose I provide a latch device 42 which cooperates with the screen to temporarily hold the same in its transverse position adjacent the discharge opening 14. This latch device may comprise an arm 43 pivotally mounted upon a bracket 44 and carrying a roller 45 for engagement with the lower portion of the screen. The arm 43 is adapted to be lifted by a float 46 which is connected with the arm.

As the level of liquid collected in the container 21 rises, the float 46 lifts the arm 43. When the liquid level reaches a predetermined height the roller 45 acts as a stop which engages the lower portion of the screen and prevents the latter from being swung to its transverse position adjacent the opening 15. If the electric fan is 40 started while the device 42 is in its elevated position, the screen will remain adjacent the opening 14 and liquid will be supplied to the screen from the container 21. When the level of the liquid in the container 21 falls, the device 42 45 will be lowered and the screen will be moved outwardly to its position adjacent the opening 15 and will then receive liquid from the tank 20. Whenever the fan 18 is stopped the screen will return to its rest position and when the fan is 50 restarted, it will either be held adjacent the opening 14 or will move to its position adjacent the opening 15, depending upon whether there is sufficient liquid in the container 21 to lift the latch device 42.

The air intake passage 11 may be provided with a filter 48 through which the air passes and which removes particles of dust or like matter therefrom. This filter may be a screen formed of wire or cloth fabric or a body of 60 matted wool fibres, or a combination of such materials.

In Figs. 5 and 6 of the drawing I have shown air directing hoods which may be used with my improved humidifying apparatus. In Fig. 5 I 65 have shown a hood 50 mounted on the discharge side of the humidifying device 51 to direct the moistened air in a desired direction, for example, into the air intake of a hot-air furnace. The air intake opening of the device may have 70 a filtering screen 48a thereon. In Fig. 6 I have shown hoods 52 and 53 mounted respectively on the intake and discharge sides of a humidifying device 54. The hood 52 may be extended through the opening of a window or wall 55 to 75

draw in air from a different room or from the outside of the building. The hood 53 is constructed to direct the discharge of moistened air upwardly so that it will not cause harmful effects by being blown directly on workmen or apparatus.

In the arrangement of Fig. 6 the intake hood 52 may have an opening 56 which connects the passage of the hood with the space or room to the inside of the wall 55. A butterfly valve 57 may be mounted to swing in the passage of the hood 52 so that in one position it closes or partially closes the opening 56 and in its other position it closes or partially closes the passage of the hood. A suitable electric actuating device 58 may be operatively connected with the pivot shaft of the valve 57 to swing the same. The device 58 may be automatically controlled by a thermostat 59 so that when the room temperature is high the valve 57 will be moved to a position closing the opening 56 and cold air will then be taken from outside the wall 55, and when the room temperature is low the valve will close the opening of the hood 52 and air will then be taken from the inside of the wall through the opening 56. The intake hood 52 may also be fitted with a filter screen 48b.

From the foregoing description and the accompanying drawing it will now be readily understood that I have provided improved automatic humidifying apparatus in which the movement of a foraminous absorbent screen to a desired operative position also causes automatic starting of the supply of liquid to the screen. It will also be understood that the movement of the screen to its desired operative position is caused by the flow of air such that by automatically controlling the operation of a fan or air supply and the level of liquid in a liquid supply tank, the operation of my improved humidifying apparatus is rendered entirely automatic.

Having thus described my invention, I claim:

1. In combination, a housing having means providing an air passage, a foraminous screen, means mounting said screen for movement to a position extending across said passage such that the air flowing in the passage must pass therethrough, means for forcing air through said passage and screen, and means for supplying liquid to the screen, the last mentioned means being automatically rendered effective by such movement of the screen.
2. In combination, a housing having means providing an air passage, a foraminous screen, means mounting said screen for movement to a position extending across said passage such that air flowing in the passage must pass through the screen, means for forcing air through said passage and screen, and a liquid containing chamber adjacent said passage, said screen having a portion adapted to dip into the liquid of the chamber upon movement thereof to its position across the passage.
3. In combination, a casing having a chamber provided with a discharge opening, means for blowing air into said chamber, a foraminous screen, means mounting said screen to be swung by the air flow to a position extending across said discharge opening, and a liquid supply, said screen having a portion thereof movable into cooperation with said liquid supply by swinging of the screen.
4. In combination, a casing having a chamber provided with a discharge opening, means for blowing air into said chamber, a foraminous
5. In a humidifier, a casing having an air passage, a fan operable for forcing air through said passage, an absorbent sheet adapted to have air forced therethrough by said fan, said sheet extending transversely of said passage and being mounted to swing from one transverse position to another, and a pair of liquid containers 15 adjacent said passage, said sheet having a portion engageable with the liquid of one container when the sheet is in one of its positions and another portion engageable with liquid in the other container when the sheet is in its other position. 20
6. In a humidifier, a casing having an air passage, a fan operable for forcing air through said passage, an absorbent sheet adapted to have air forced therethrough by said fan, said sheet extending transversely of said passage and being 25 mounted to swing from one transverse position to another, and liquid supply and collecting containers adjacent the top and bottom of said passage, said sheet having a portion adapted to engage the liquid in said supply container when the sheet is in one position and another portion adapted to engage liquid in the collecting container when the sheet is in its other position. 30
7. In a humidifying device, a casing having a discharge opening, a fan operable to force air toward said opening, a liquid containing tank, a foraminous absorbent screen adapted to be swung by the fan discharge to a position extending across said opening and having a portion movable into the liquid of said tank upon 40 swinging of the screen to said position, and means automatically maintaining a desired liquid level in said tank. 35
8. In a humidifying device, a casing having a discharge opening, a fan operable to force air toward said opening, a liquid containing tank, a foraminous absorbent screen adapted to be swung by the fan discharge to a position extending across said opening and having a portion movable into the liquid of said tank upon 45 swinging of the screen to said position, and means including a float operated valve for automatically maintaining a desired liquid level in said tank. 50
9. In a humidifying device, a casing having a discharge opening, a fan operable to force air toward said opening, a liquid containing tank, a foraminous absorbent screen adapted to be swung by the fan discharge to a position extending across said opening and having a portion movable into the liquid of said tank upon 55 swinging of the screen to said position, and a humidostat for automatically starting and stopping said fan. 60
10. In a humidifying device, a casing having a discharge opening, a fan operable to force air toward said opening, a liquid containing tank, a foraminous absorbent screen adapted to be 65 swung by the fan discharge to a position extending across said opening and having a portion movable into the liquid of said tank upon swinging of the screen to said position, means automatically maintaining a substantially constant liquid level in said tank, and means operable for automatically starting and stopping said fan. 70
11. In a humidifying device, a casing having

5 a discharge opening, a fan operable to force air toward said opening, a liquid containing tank, a foraminous absorbent screen adapted to be swung by the fan discharge to a position extending across said opening and having a portion movable into the liquid of said tank upon swinging of the screen to said position, means including a float operated valve for automatically maintaining a desired liquid level in said container, and a humidostat automatically controlling the operation of said fan.

10 12. In a device of the character described the combination of a casing having a discharge passage, a fan operable to force air through said passage, a tank above said passage, and an absorbent foraminous sheet hinged adjacent an edge of said tank to extend down into said passage in front of said fan and having an angularly disposed portion overhanging said edge of the 15 tank.

13. In a device of the character described the combination of a casing having an inclined wall provided with a discharge opening, a fan operable to force air toward said opening, a liquid containing tank, and an absorbent foraminous sheet hinged adjacent an edge of said tank with one portion extending down in front of the fan and another portion overhanging the tank, said sheet being adapted to be swung by the fan discharge to simultaneously move said one portion into position across the inclined discharge opening and said overhanging portion into the liquid 20 of said tank.

25 14. In a device of the character described the combination of a casing having spaced vertical and inclined walls provided with openings communicating with a chamber between the walls, a fan operable to force air into said chamber

5 through the opening of the vertical wall, a liquid containing tank adjacent the top of said chamber, and an absorbent foraminous screen hinged adjacent the top of said chamber with one portion extending down into the chamber and another portion overhanging the tank, said screen being adapted to be swung by the fan discharge to shift the downwardly extending portion from a position extending across the opening of the vertical wall to a position extending across the 10 opening of the inclined wall and to simultaneously move said overhanging portion into the liquid of the tank.

15 15. In a device of the character described the combination of a casing having spaced vertical and inclined walls provided with openings communicating with a chamber between the walls, a fan operable to force air into said chamber through the opening of the vertical wall, a liquid containing tank adjacent the top of said chamber, an absorbent foraminous screen hinged adjacent the top of said chamber with one portion extending down into the chamber and another portion overhanging the tank, said screen being adapted to be swung by the fan discharge to shift 20 the downwardly extending portion from a position extending across the opening of the vertical wall to a position extending across the opening of the inclined wall and to simultaneously move said overhanging portion into the liquid 25 of the tank, a liquid collecting container adjacent the bottom of said chamber, and means operable to prevent swinging of the screen toward said inclined wall when the liquid in the collecting container exceeds a predetermined 30 level.

35 HERMAN W. PATTERSON.
